UNITED STATES PATENT OFFICE

2,177,592

FUSED PLUG

Scipione M. Del Camp, Maywood, Ill., assignor to
 Cinch Manufacturing Corporation, Chicago,
 Ill., a corporation of Illinois

Application November 5, 1946, Serial No. 109,368

3 Claims. (Cl. 200—115.5)

This invention relates to electrical plug members or the like and more particularly to plug members provided with a fuse used to bridge one of the circuit lines.

5 Referring to the drawing, in which I have illustrated a preferred embodiment of my invention:

Figure 1 is a front elevation of my improved electrical plug member;

Fig. 2 is a top plan view of the plug member 10 shown in Fig. 1;

Fig. 3 is a side elevation of the plug member shown in Fig. 1;

Fig. 4 is a bottom plan view of the plug member shown in Figs. 1-3;

15 Fig. 5 is a section taken along the line 5—5 of Fig. 2, part of the section passing through one of the contact terminals;

Fig. 6 is a section taken along the line 6—6 of Fig. 2;

20 Fig. 7 is a section taken along the line 7—7 of Fig. 1;

Fig. 8 is a section taken along the line 8—8 of Fig. 5; and

Fig. 9 is a section taken on the line 9—9 of Fig. 7.

A preferred form of my improved plug member, as illustrated in the drawing, has a body portion providing insulating plates 1 and 2 spaced one from another by means of the washers 3. The upper plate 1 carries a fuse clip assembly and wire-receiving lugs and flat metal contact terminals 4 extending beneath the plate 2 for engagement with a cooperating socket. The terminals 4 serve also to maintain the insulating plates in fixed relation in a manner hereinafter described. The plate 1 has a number of cut-away sides 5, as most clearly shown in Figs. 7 and 8. A cup-shaped shield 6 is provided with shoulders (not shown) adapted to fit between the plates 1 and 2 so as to secure the shield to the plate in the manner described in United States Patent No. 2,031,564 issued to C. L. Knutson. The shield 6 is adapted to protect the fuse as well as the wire connections, as will be understood by those skilled in the art.

The top plate 1 is provided with a metallic conducting plate 7 having one side adjacent the outer surface of the plate 1, as most clearly shown in Figs. 5 and 6. A pair of fuse clips 8 and 9 are located in spaced relation one to another on the outer side of the plate 1. Each of the fuse clips has a base 10 and upstanding spaced resilient side walls 11 providing an opening for receiving opposed ends of a fuse 12. The side walls 11 of each of the clips 8 and 9 are bowed and adapted

to expand when an end of the fuse 12 is inserted therebetween and then contract to hold the fuse member in place. As a result of the particular construction of the clips 8 and 9 the fuse member may be readily removed or replaced. 5 The base 10 of the fuse clip 8 is superposed upon an end of the metal conducting plate 7 and the clip 8 is secured to the insulating plate 1 and at the same time fixed in electrical contact with the conducting plate 7 through means such as a rivet 10 13 (Fig. 9) extending through the parts. The cooperating clip 9 has a base portion 10 superposed upon a leg 14 (Fig. 6) of a wire-receiving lug 15. The clip 9 and the lug 15 are secured to the plate by means such as a rivet 13^a extending through the parts. The rivet 13^a serves also to maintain the clip and wire-receiving lug in electrical contact. An aperture 15^a is formed in the lug 15 (Fig. 5) in my preferred form for receiving a lead-out wire which may be soldered 15 to the lug. Another wire-receiving lug 16 (Figs. 7 and 8) is secured to the insulating plate 1 and fixed in permanent electrical contact to one of the contact terminals 4 in a manner hereinafter described. A lead-out wire (not shown) may be 20 soldered or otherwise secured to the lug 16.

The contact terminals 4 are provided, in my preferred form, with a rectangular-shaped socket-engaging portion 17 extending beneath the plate 2 as shown in Figs. 5 and 9. Shoulders 18 30 are formed at one end of the rectangular-shaped portion of the terminals engaging the outer surface of the plate 2 (Figs. 5 and 9) and a shank 19 extends upwardly between the shoulders through the plates 1 and 2 and the washers 3 as shown in 35 Fig. 5. The free end of the shank 18 of each of the terminals 4 is preferably bifurcated so as to provide portions 20. The bifurcated portions 20 of one of the terminals 4 engage an outside surface of the metal conducting plate 7 (Figs. 5, 6, 40 and 8) and the bifurcated portions 20 of the other terminal 4 engage an outside surface of the wire-receiving lug 16 (Figs. 7 and 8). As a result of this construction the plates 1 and 2 and the respective metal conducting plate 7 and lug 45 16 are maintained in secure assembly between the shoulders 18 of the contact terminals and the bifurcated portions 20.

As a result of my invention I have provided a plug member of relatively simple construction 50 having a detachable fuse in series with one side of the line. The parts of my improved plug member are inexpensively manufactured and easily put together so as to provide a compact and foolproof assembly.

Although I have illustrated and described a preferred form of my invention, I do not wish to be limited thereby because the scope of my invention is best set forth in the following claims.

5 I claim:

1. An electrical plug member comprising at least two insulating plates in superposed relation, a pair of contact terminals extending beneath said plates and having means securing said plates together, a pair of spaced fuse clips secured to the upper of said plates, means connecting one of said clips with one of said terminals, a wire-receiving means in electrical contact with said other clip, a wire-receiving means in electrical contact with the other of said terminals, and a shield cap as part of the plug assembly.
2. An electrical plug member comprising a pair of thin insulating plates in superposed relation, a pair of contact terminals extending beneath the lower of said plates, said terminals having spaced portions maintaining said plates between them for securing said plates together, a pair of spaced fuse clips secured to the upper of said plates, means electrically connecting one of said clips with one of said terminals, a wire-receiving lug in electrical contact with said other clip and a wire-receiving lug secured to the other of said

terminals and in electrical contact with said other terminal:

3. An electrical plug member comprising a pair of thin insulating plates in superposed relation, a pair of spaced fuse clips secured to the upper of said plates, a metal plate adjacent a surface of the upper of said plates and in electrical contact with one of said clips, a wire-receiving lug in electrical contact with said other clip, another wire-receiving lug disposed upon the upper of said plates and a pair of contact terminals extending through said plates and beneath said plates for electrical connection with a cooperating socket member, one of said terminals having a portion at its free end engaging an outer surface of said metal plate whereby said metal plate is secured to said upper insulating plate and the other of said terminals having a portion at its free end engaging said other wire-receiving lug whereby said lug is secured to said upper plate, and said terminals having a portion engaging the lower of said insulating plates whereby said plates are held together between the portions of said terminals engaging said respective metal plate and wire-receiving lug and the portions of said terminals engaging said lower plate.

SCIPIONE M. DEL CAMP.
